UNITED STATES PATENT OFFICE

117,618

DESIGN FOR A TEXTILE FABRIC OR SIMILAR ARTICLE

Benjamin Gordon, New York, N. Y.

Application August 30, 1939, Serial No. 86,942

Term of patent 3½ years

To all whom it may concern:

Be it known that I, Benjamin Gordon, a citizen of the United States, residing at New York, in the county of New York and State of New York, have invented a new, original, and ornamental Design for a Textile Fabric or Similar Article, of which the following is a specification, reference being made to the accompanying drawing, forming a part thereof.

The figure is a plan view of the fabric embodying the design.

I claim:

The ornamental design for a textile fabric or similar article, substantially as shown.

BENJAMIN GORDON.
